UNITED STATES PATENT OFFICE.

EDGAR F. HATHAWAY, OF WELLESLEY, AND WALTER BIXBY, OF BOSTON, MASSACHUSETTS, ASSIGNORS TO SHAWMUT ENGINEERING COMPANY, OF BOSTON, MASSACHUSETTS, A CORPORATION OF MASSACHUSETTS.

TUFT TUBE FRAME FOR WEAVING.

Application filed January 29, 1923. Serial No. 615,512.

To all whom it may concern:

Be it known that we, EDGAR F. HATHAWAY and WALTER BIXBY, citizens of the United States, and residents, respectively, 5 of Wellesley, in the county of Norfolk and State of Massachusetts, and Boston, in the county of Suffolk and State of Massachusetts, have invented certain new and useful Improvements in Tuft Tube Frames 10 for Weaving, of which the following is a specification.

This invention is concerned with the operation of removing from its carrier chain a tuft tube frame such as is used in weaving Axminster carpets or similar pile fabrics, and is intended to provide simple but absolutely effective means for assuring the removal of the tuft tube frame from its carrier chain in case the suspension hangers 20 should become wedged or stuck in the chain during the weaving operation.

To this end the invention embraces a construction and arrangement of tube frame suspension means so located as to be positively engaged by overhanging portions of the transfer cam or mechanism by which the frame is transferred from its carrier frame to position to deliver the yarn for insertion in the fabric being woven.

30 The invention comprises both provision for engaging a lateral portion of the transfer mechanism by which the tube frame is removed for use, and also a novel construction of the hook member of the suspension means by which temporary interlocking engagement between the transfer mechanism and the hook arm is effected in case, by reason of bending or breakage, the provision for lateral engagement should not be effective.

These and other features of the invention will be particularly explained in the following specification and will be defined in the claims hereto annexed.

45 In the accompanying drawings:

Figure 1 illustrates an assembled view in front elevation of one end of the tube frame in its relation to the portion of the transfer mechanism which latter is shown partly in 50 section.

Figure 2 is an end elevation of the sus-

pension members attached to the carrier bar.

Figure 3 is an end elevation of a modified form of hook arm.

Figure 4 being a side elevation showing 55 that portion of the hook arm adjacent to the transfer-engaging projection or boss.

Figure 5 is a front elevation showing the carrier bar and the transfer mechanism in operative relation with lateral engagement 60 between the tube frame and the transfer mechanism for forcing down the tube frame from the chain.

Figure 6 is a detail plan view partly in section on the plane indicated by broken 65 line 6—6 on Figure 5.

Figure 7 is an end elevation on the plane 7—7 of Figure 5.

In the practice of tube frame weaving difficulty is sometimes experienced by the failure of the tube frame to descend along with the transfer mechanism by its own weight when the chain-engaging hooks are released from engagement, an occurrence 70 which may take place from a variety of causes.

Our present improvement deals with this problem by providing means arranged to have engagement with an overhanging lateral portion of the transfer cam, and to 75 further insure such disengagement in case of breakage or injury to any of the parts constructs the hook arm itself so as to be similarly engaged by another overhanging part of the transfer mechanism, thus rendering absolutely certain the disengagement of the tube frame from the chain in case of 80 clogging or binding of the suspension means.

In the form illustrated in Figure 1 we 85 have shown one end portion of a tube frame embracing the longitudinal carrier bar 1, to which is secured the suspension arm 2, formed at its upper end with an outwardly offset chain-penetrating prong 3, which 90 passes between the links *t* of the carrier chain, said arm also being provided with a projecting ear 4 forming a bearing for the journal of the yarn-carrying spool.

The cooperating suspension member comprises a hook arm 5 made of material sufficiently rigid to avoid being distorted under 100

stresses of ordinary usage. This hook arm 5, is provided at its upper end with the chain-engaging hook 6, and at its lower end with an eye 7, forming a bearing surrounding or partly surrounding a fulcral pin 9 which passes transversely through the carrier bar 1, adjacent to its lower corner. A spring 8 normally presses the hook arm outward.

10 The usual transfer mechanism comprises a so-called transfer cam 12, which has an inwardly projecting lip 14, at its upper end and an inwardly projecting horn 15 at its lower end with opposed lateral wings 16, thus forming a cradle or seat for supporting and carrying down and up again the tube frame when the hook is released from the chain, this cam being itself supported by suitable arms or rods 13, which are not 20 concerned with this invention.

Intermediate of its ends the hook arm 5, is formed with a struck out integral projecting ear 10 arranged in the path of the projecting lip 14, which overhangs said projection. The transfer cam moves inward pressing the hook arm against the bracket 2 so as to release the hook by engagement with the chain after which the transfer mechanism descends carrying the ends of the tube 30 frame seated on its lower horn 15 and positioned between its lateral wings 16.

In case binding of the parts prevents the weight of the tube frame from descending with the transfer device, the projecting lug 35 10 will be engaged and temporarily interlocked with the descending lip 14, so that the tube frame will be pulled positively downward. As the hook arm 5 is made of relatively rigid material it will readily sustain the strain of such downward pull without buckling or springing away from such engagement.

The construction may be made even more rigid if, instead of partly severing the projecting lug 12, it is struck out as an integral boss as shown at 10^a in Figures 3 and 4 without severing any part of the metal in forming the projection.

Since the rigid hook arm is combined 50 with a fulcral pin this affords additional means of positively effecting such interlocking engagement with the transfer mechanism by merely lengthening either end of the fulcral pin to be engaged by a lateral 55 overhanging portion of the transfer mechanism, to wit, one of the side wings 16.

Figures 5, 6 and 7 illustrate the details of this construction in which the fulcral pin 7^a is provided with a lateral projecting portion 7^b disposed, when the transfer mechanism moves horizontally inward, to engage the carrier bar so that the projecting portion of the pin lies between the horn 15 and the overhanging side wing 16.

65 The advantage of providing the rigid

hook arm and its fulcral pin with projections for engaging both the middle and side portions of the transfer cam or mechanism is that an accident which ordinarily would distort or injure one part is not likely to 70 injure both, and in each case the transmission strain is ultimately brought to bear upon the carrier bar through the agency of the interior or protected portion of the fulcral pin. 75

What we claim is:

1. In a tuft tube frame for weaving, the combination with a carrier bar and its suspension bracket, of a rigid hook arm pivotally fulcrumed to swing into and out of engagement with the tube frame carrier chain by action of suitable transfer mechanism, and means disposed to be engaged by an overhanging part of the transfer mechanism in its downward movement and transmit a downward pull on the tube frame through said fulcral connection, substantially as described. 80

2. In a tuft tube frame, the combination with a longitudinal carrier bar and its suspension bracket, of a pivotal hook member cooperatively combined with the suspension bracket to releasably engage the carrier chain, said pivotal hook being provided with a projecting member arranged to be engaged by the transfer cam in its downward movement in order to insure the removal of the tuft tube frame from the carrier chain, substantially as described. 90

3. In a tuft tube frame for weaving, the combination with a longitudinal carrier bar and its suspension bracket, of a pivotal hook-arm cooperatively associated therewith to releasably engage a carrier chain, the fulcral pin of said hook arm being extended laterally to be engaged by the transfer device as the transfer device moves downward whereby the removal of the frame from the chain is positively assured, substantially as described. 100

4. In a tuft tube frame for weaving, the combination with a longitudinal carrier bar and its suspension bracket, of a rigid hook arm pivotally fulcrumed to swing into and out of supporting engagement with a carrier chain, the fulcral pin being extended to project into engagement with a lateral portion of suitable transfer mechanism, said pivotal hook arm also having a supplemental transfer engaging projection struck out from the arm stud, substantially as described. 115

5. A hook arm for the suspension bracket of a tuft tube frame embracing an arm of substantial rigid material provided with a chain-engaging hook at one end and a fulcral bearing at the other and having an integral boss projecting outwardly intermediate of its ends to form temporary interlocking engagement with an overhanging 120 130

portion of frame-transferring mechanism to insure removal from the carrier chain, substantially as described.

6. In a tube frame for tuft weaving, the combination with a carrier bar and its suspension bracket, of a rigid pivotal hook-arm and its fulcral support, and positive releasing means comprising a projecting member arranged to lie in the path of an overhang-

ing portion of the transfer device and acting to transmit the downward movement of the transfer device through said pivotal fulcrum to the carrier bar, substantially as described.

In witness whereof, we have subscribed the above specification.

EDGAR F. HATHAWAY.
WALTER BIXBY.
